(57)

CLAIM

The ornamental design for a slurry pump, as shown and described.

DESCRIPTION

2. Slurry pump

2.1 : Perspective

2.2 : Front

2.3 : Back

2.4 : Left

2.5 : Right

2.6 : Top

2.7 : Bottom

(Continued)

The broken lines depict portions of the slurry pump that are not considered part of the claimed design.

1 Claim, 7 Drawing Sheets
